UNITED STATES PATENT OFFICE.

JULIUS B. WANTZ, OF CHICAGO, ILLINOIS, ASSIGNOR TO VICTOR ELECTRIC COMPANY, OF CHICAGO, ILLINOIS, A CORPORATION OF ILLINOIS.

X-RAY TABLE.

1,216,633.

Specification of Letters Patent. Patented Feb. 20, 1917.

Application filed January 15, 1915. Serial No. 2,481.

To all whom it may concern:

Be it known that I, JULIUS B. WANTZ, a citizen of the United States, residing at Chicago, in the county of Cook and State of Illinois, have invented a new and useful Improvement in X-Ray Tables, of which the following is a specification.

My invention relates more particularly to X-ray tables adapted for either fluoroscopic or radiographic work; and my objects, generally stated, are to provide a table comparatively light in weight and economical to manufacture; to provide a table so constructed that it may be readily conditioned for either fluoroscopic or radiographic work, without the loss of flexibility or range in either case, the radiographic work involving the taking of either single röntgenograms or stereoscopic röntgenograms; to provide against the fogging of the sensitized plates by reflected rays; and to protect the operator from the action of the rays.

Referring to the accompanying drawings—

Figure 1 is a plan view of a table constructed in accordance with my invention. Fig. 2 is a section taken at the line 2 on Fig. 1 and viewed in the direction of the arrow. Fig. 3 is a view in side elevation of the upper portion of the table, the supports therefor being shown in dotted lines, and a portion of the table-top being broken away. Fig. 4 is a bottom plan view of the table-top; and Fig. 5, a face view of one of the pair of similar ray-obstructing plates employed.

In the drawings, I have illustrated my invention as embodied in a table adapted for use in producing either stereoscopic, or single, röntgenograms, and fluoroscopic work, as this is desirable under ordinary conditions of practice, though as hereinafter stated, certain features of my invention are applicable to a table embodying certain only of the above features.

The table-top shown is formed of a continuously extending section 6 of material transparent to X-rays, a desirable material being aluminum. Secured to the undersides of the section 6 are side-rails 7 containing on their inner surfaces upper and lower grooves, respectively, 8 and 9 at opposite

sides of the table. The lower grooves 9 contain rails 10 forming tracks for a carriage 11 longitudinally reciprocable lengthwise of the table-top, the carriage 11 carrying rollers 12 at its opposite edges which engage the rails 10. The provision of the carriage is in accordance with common practice, especially when it is desired that stereoscopic röntgenograms be produced, and it will be readily understood that the carriage may be provided of any desirable form and operated in any desirable manner. In the construction illustrated, the carriage 11 may be formed of material opaque to X-rays and is provided with a propelling spring 13 connected at its opposite ends to a rigid portion of the table-top and to the carriage 11, as represented at 14 and 15, respectively. The carriage 11 carries a lug 16 at one side adapted to engage with a trigger device 17. The carriage 11 is provided with any suitable means for releasably securing thereto two X-ray plates to be used for successive exposures to produce a stereoscopic röntgenogram. In the construction illustrated, the X-ray plates are adapted to be applied to the upper surface of the carriage 11 and are held in place by the reversible clips 18, 80 these clips being adjustable toward and away from each other for different sized plates and reversible for clamping a plate to the upper surface of the carriage 11 when the plate is in an envelop, as represented at 20, 85 or when the plate is in a plate-holder, as represented at 20, as by engagement of the lugs 21 on the clips 18.

The parts described are so proportioned, 90 in accordance with common practice, that when the carriage is in the position illustrated in Fig. 4, namely, a position wherein the trigger 17 interlocks with the lug 16, the center of the plate 20, namely the one to be first exposed, will register with the point of intersection of two lines 22 and 23 arranged at right-angles to each other on the upper surface of the section 6 of the table-top; and that the center of the succeeding plate, as for example, that in the plate-holder 20 and on which the second exposure is to be made, will, upon releasing the trigger 17, thus permitting the spring 13 to operate, be caused

to register with the point of intersection of the lines 22 and 23, or in other words, will be carried to the same position for exposure, as that occupied by the first plate at the time of making the first exposure.

- 5 The table-top may be supported in any suitable manner, the support shown in the drawing being shown in part only, at 24, but as the particular form of support for the 10 table-top forms no part of the present invention, a detailed description thereof appears to be unnecessary. Coöoperating with the section 6 of the table-top are slides represented at 25, these slides, which in the 15 illustrated embodiment of my invention are of similar size and shape and provided with handles 26, extending at their opposite sides into the channels 8 and longitudinally adjustable therein independently of each other 20 to extend in mutual abutting relation at their inner ends or in varying spaced relation, these slides being formed of material opaque to X-rays, it being preferred that each be made of sheet-iron either alone, or 25 with a covering of lead, the sheet-iron being preferably about one-eighth of an inch thick. When the table is to be used for the making of stereoscopic radiograms, the operator will adjust the slides 25 lengthwise of the table-top to present between their opposing ends a space of such width that an X-ray plate centered relative to the intersection of the lines 22 and 23 may be exposed to the X-rays emitted from an X-ray tube, not 30 shown, which would be located above the table. With the slides 25 in the adjusted position referred to, the slide at the right-hand side of Fig. 1 will serve to prevent exposure of the plate at the right-hand end of 35 the carriage (Fig. 4), namely, the one which is to receive the second exposure; and when the carriage 11 has been shifted to the left in Fig. 4 to position the plate at the right-hand end of the carriage 11 for receiving the second 40 exposure, the slide 25 at the left-hand end of Fig. 1 will serve to prevent exposure to the X-rays, of the first plate which was 45 exposed.
- The slides 25 being adjustable toward and 50 away from each other, a space of any desired width may be provided at their adjacent ends and thus any desired width of section transparent to X-rays may be provided in the table-top. This is of advantage, especially 55 where plates of different sizes are employed as the slides 25 may be adjusted to prevent the passing of X-rays along opposite sides of the X-ray plate which reduces danger of fogging of the X-ray plates by reflected X-rays and danger to the feet of the operator from subjection to the rays. In this 60 way even better protection is given to the plate before and after exposure and to the operator, than would be possible with a table 65 provided with immovable opaque plates.

In the making of single röntgenograms, the usual practice, because of its convenience, is to place the X-ray plate to be exposed on the top of the table beneath the patient. When the table is used in this manner, the 70 slides 25 would be adjusted on the table-top into endwise abutting relation. This feature of the table is very desirable as the slides 25 by reason of their relative stiffness and their position in the table-top serve as a stiffening 75 medium for the latter. It is well understood that the thicker the section 6 of the table-top, the less transparent to X-rays it becomes, and furthermore, the more expensive. The table-top should, however, where the 80 X-ray plate is placed on its upper surface and the patient lies upon this plate, be sufficiently stiff to prevent it from sagging to such an extent that the X-ray plate under the weight of the patient will not break. By 85 providing the slides 25 the section 6 of the table-top may be made relatively thin as the slides 25 will, when adjusted to the innermost position, render it sufficiently stiff to prevent objectionable sagging.

In using the table for fluoroscopic work, the slides 25 would be withdrawn from the table-top which would render the entire table-top transparent to X-rays emitted from an X-ray tube, which in practice would be located, for this class of work, beneath the table-top. The operator would therefore be enabled to make a fluoroscopic examination of the entire body of the patient, it being understood that the carriage 11 would be 90 removed in making such an examination.

In the type of table in which the opaque shields on the table are stationary, the fluoroscopic field was equal to about one-third the total area of the table-top, one of the other thirds being rendered opaque by one sheet for protecting the X-ray plate in the right end of the carriage 11 before exposure and the remaining third being rendered opaque by the other shield for protecting the X-ray 100 plate in the left-hand end of the carriage 11 after exposure. By making these shields movable in accordance with my invention, better protection is given the X-ray plates before and after exposure when the table is 105 used for the taking of stereoscopic röntgenograms, the area of the stereoscopic field is greatly increased (in the particular construction illustrated to a 3-fold degree) and a table-top stiff enough for the taking of 110 single röntgenograms is provided. In this way a table constructed in accordance with the preferred embodiment of my invention with a top as described, can be used either as an X-ray table with a stereoscopic plate-shifter, as a radiographic table for use in taking single röntgenograms, or as a fluoroscopic table, without any loss of range or 115 flexibility.

While I have illustrated and described my 120

improvement as embodied in a table adapted for both fluoroscopic and radiographic work, it will be readily understood that it may be embodied in a table designed for radiographic work alone.

What I claim as new and desire to secure by Letters Patent is—

1. In a combined fluoroscopic and radiographic X-ray table, the combination of a 10 table-top of material transparent to X-rays, and members of material opaque to X-rays relatively movable toward each other for radiographic work and relatively movable away from each other to enlarge the transparent field of the table-top, for fluoroscopic work.

2. In a table for radiographic work and fluoroscopic work, the combination of a 20 table-top of material transparent to X-rays, and plates of material opaque to X-rays movable to a position on the table in which they oppose portions only of the table-top and render a comparatively small area of said top transparent for radiographic work, 25 and to a position in which a relatively large area of the table-top is rendered transparent for fluoroscopic work.

3. In a table for radiographic work and fluoroscopic work, the combination of a 30 table-top of material transparent to X-rays, and plates of material opaque to X-rays movable to a position in which they oppose portions only of the table-top and render a comparatively small area of said top transparent for radiographic work, and removable from the table to free said table-top of obstruction to X-rays for fluoroscopic work.

4. In a table for radiographic work and fluoroscopic work, the combination of a 40 table-top of material transparent to X-rays, and members of material opaque to X-rays mounted on the table beneath said table-top and movable to a position in which they oppose portions only of the table-top and render a comparatively small area of said table-top transparent for radiographic work, and to a position in which a relatively large area of the table-top is rendered transparent for fluoroscopic work.

5. In a table for radiographic work and fluoroscopic work, the combination of a 50 table-top of material transparent to X-rays, and members of material opaque to X-rays movable on the table longitudinally of the latter to a position in which they oppose portions only of the table-top and render a comparatively small area of said top transparent for radiographic work, and to a position in which a relatively large area of the table-top is rendered transparent for fluoroscopic work.

6. In a table-top for radiographic work and fluoroscopic work, the combination of a 60 table-top of material transparent to X-rays,

and plates of material opaque to X-rays movable on said table longitudinally thereof to a position in which they oppose portions only of the table-top and render a comparatively small area of said table-top transparent for radiographic work and removable from the table to free said table-top of obstruction to X-rays for fluoroscopic work.

7. In a table for radiographic work and fluoroscopic work, the combination of a 70 table-top transparent to X-rays, members of material opaque to X-rays movable on the table to a position in which they oppose portions only of the table-top and render a comparatively small area of said top transparent for radiographic work, and to a position in which a relatively large area of the table-top is rendered transparent for fluoroscopic work, and shiftable X-ray-plate-carrying means beneath said opaque members for positioning the X-ray plates in succession opposite said relatively small transparent area of table-top.

8. In a combined fluoroscopic and radiographic X-ray table, the combination of a 80 table-top having the section thereof which supports the patient formed of material transparent to X-rays, members of material opaque to X-rays relatively movable toward each other for radiographic work and relatively movable away from each other to enlarge the transparent field of the table-top for fluoroscopic work, and shiftable X-ray-plate-carrying means beneath said opaque members for positioning X-ray plates in 90 succession opposite said relatively small transparent area of table-top.

9. In a table for radiographic work and fluoroscopic work, the combination of a 95 table-top of material transparent to X-rays, plates of material opaque to X-rays movable on the table to a position in which they oppose portions only of the table-top and render a comparatively small area of the table-top transparent for radiographic work and removable from the table to free said table-top of obstruction to X-rays for fluoroscopic work, and shiftable X-ray-plate-carrying means beneath said opaque members for positioning X-ray plates in 100 succession opposite said relatively small transparent area of table-top.

10. In a table for radiographic work and fluoroscopic work, the combination of a 105 table-top of material transparent to X-rays, members of material opaque to X-rays mounted on the table beneath said table-top and movable to a position in which they oppose portions only of the table-top and render a comparatively small area of the table-top transparent for radiographic work and 110 removable from the table to free said table-top of obstruction to X-rays for fluoroscopic work, and shiftable X-ray-plate-carrying means beneath said opaque members for positioning X-ray plates in 115 succession opposite said relatively small transparent area of table-top.

11. In a table for radiographic work and fluoroscopic work, the combination of a 120 table-top of material transparent to X-rays, members of material opaque to X-rays mounted on the table beneath said table-top and movable to a position in which they oppose portions only of the table-top and render a comparatively small area of the table-top transparent for radiographic work, and to a position in which a relatively large area of the table-top is rendered transparent for fluoroscopic work, and shiftable X-ray-plate-carrying means beneath said opaque 125 members for positioning X-ray plates in 130 succession opposite said relatively small transparent area of table-top.

- members for positioning X-ray plates in succession opposite said relatively small transparent area of table-top.
11. In a table for radiographic work and 5 fluoroscopic work, the combination of a table-top of material transparent to X-rays, members of material opaque to X-rays movable on the table longitudinally of the latter to a position in which they oppose portions only of the table-top and render a comparatively small area of said top transparent for radiographic work, and to a position in which a comparatively large area of the table-top is rendered transparent for 10 fluoroscopic work, and shiftable X-ray-plate-carrying means beneath said opaque members for positioning X-ray plates in succession opposite said relatively small transparent area of table-top.
12. In a table for radiographic and fluoroscopic work, the combination of a table-top of material transparent to X-rays, plates of material opaque to X-rays movable on said table longitudinally thereof to a position in 15 which they oppose portions only of the table-top and render a comparatively small area of said table-top transparent for radiographic work, and removable from the table to free said table-top of obstruction to X-rays for fluoroscopic work, and shiftable X-ray-plate-carrying means beneath said opaque members for positioning X-ray plates in succession opposite said relatively small transparent area of table-top.
13. In a radiographic table, the combination of a table-top adapted to support a patient, relatively movable members of material opaque to X-rays adapted to be adjusted to render a comparatively small area 20 of the table-top transparent to X-rays for radiographic work and a comparatively large area transparent for fluoroscopic work, and means for supporting an X-ray plate below said table-top.
14. In a radiographic table, the combination of a table-top, means for supporting an X-ray plate beneath the upper portion of said table-top, and means above the position occupied by the X-ray plate for rendering 25 the portion of said table-top above said X-ray plate transparent to X-rays, said last-mentioned means being adjustable to render a comparatively small area of the table-top transparent to X-rays for radiographic work, and a comparatively large area transparent 30 for fluoroscopic work.
15. In a radiographic X-ray table, the combination of a table-top having a section transparent to X-rays, a plurality of slides 35 of material opaque to X-rays adjustable to render a comparatively small area of the table-top transparent opposite the ends of said slides for radiographic work, and a comparatively large area transparent for fluoroscopic work, and means for supporting 40
- an X-ray plate below, and in registration with, the space presented between the ends of said slides.
16. In a radiographic X-ray table, the combination of a table-top with a section 70 thereof transparent to X-rays, relatively movable members opaque to X-rays adapted to be adjusted to render a comparatively small area of the table-top transparent to X-rays for radiographic work and a comparatively large area transparent for fluoroscopic work, and a shiftable X-ray-plate-holding member below said table-top, one of said relatively movable members serving to prevent X-rays from striking one of said 80 X-ray plates on said shiftable member.
17. In a radiographic X-ray table, the combination of a table-top with its top section formed of material transparent to X-rays, a pair of relatively movable members 85 opaque to X-rays disposed beneath, and in registration with, said transparent section of the table-top, and a shiftable plate-holding member below said relatively adjustable members adapted to support a pair of plates, 90 said relatively adjustable members being adapted to be adjusted to render a comparatively small area of the table-top transparent to X-rays for radiographic work and a comparatively large area transparent for fluoroscopic work and adapted to be so positioned relative to the X-ray plates on said shiftable member that when said shiftable member is in one position for exposing one of its plates, one of said relatively movable members 95 will prevent the other of said X-ray plates from being exposed to the X-rays, and when said shiftable member is shifted to expose the other X-ray plate thereon, the other of said relatively movable members 100 will prevent the X-ray plate first exposed from being subjected to the X-rays.
18. In a combined fluoroscopic and radiographic X-ray table, the combination of a table-top having a section thereof which 105 supports the patient formed of material transparent to X-rays, and means on said table-top adjustable to different positions thereon and serving, when in one position, to stiffen said transparent section against 110 undue sagging under the weight of the patient and removable from such position to a position in which they will be out of the path of the X-rays when the table is being used for fluoroscopic work.
19. In a combined fluoroscopic and radiographic X-ray table, the combination of a table-top having a section thereof which 115 supports the patient formed of material transparent to X-rays, and slides on said table-top adjustable to different positions thereon and serving, when in one position, to stiffen said transparent section against 120 undue sagging under the weight of the patient and removable from such position to 125
- 130

a position in which they will be out of the path of the X-rays when the table is being used for fluoroscopic work.

20. A combined fluoroscopic and radiographic X-ray table provided with inwardly opening channels and having a top-section for supporting the patient formed of material transparent to X-rays, and slides of relatively stiff material opaque to X-rays 10 adjustably mounted in said channels.

21. In a combined fluoroscopic and radiographic X-ray table, the combination of a table-top with its upper section upon which the patient rests formed of material transparent to X-rays, a pair of slides of material opaque to X-rays on said table-top longitudinally adjustable thereon and adapted to be moved into and out of registration with said transparent section and serving, 15 when adjusted to innermost position, to stiffen said transparent section against sagging under the weight of the patient, and a shiftable member below said slides adapted to carry a pair of X-ray plates, for the purpose set forth.

22. In a combined fluoroscopic and radiographic X-ray table, the combination of a table-top having a section thereof which supports the patient formed of material transparent to X-rays, and means on said table-top opaque to X-rays, adjustable to different positions thereon and serving, when in one position, to stiffen said transparent section against undue sagging under the weight of the patient and removable from such position to a position in which they will be out of the path of the X-rays when the table is being used for fluoroscopic work.

30 23. In a combined fluoroscopic and radiographic X-ray table, the combination of a table-top having a section thereon which supports the patient formed of material

transparent to X-rays, and slides opaque to X-rays on said table-top adjustable to different positions thereon and serving, when in one position, to stiffen said transparent section against undue sagging under the weight of the patient and removable from such position to a position in which they will be out of the path of the X-rays when the table is being used for fluoroscopic work.

24. In a combined fluoroscopic and radiographic X-ray table, the combination of a table-top formed of material transparent to X-rays, members of material opaque to X-rays mounted on the table to be relatively movable lengthwise of the table-top toward and away from each other to vary the transparent field of the table-top and serving, when adjusted to a certain position, to stiffen said transparent section against sagging under the weight of the patient, and a shiftable member below said first-named members adapted to carry a pair of X-ray plates, for the purpose set forth.

25. In an X-ray table, the combination of a table-top of material transparent to X-rays, and members of material opaque to X-rays extending practically co-extensive with said transparent section and each movable along said table-top independently of the other.

26. In an X-ray table, the combination of a table-top of material transparent to X-rays, adjustable means for rendering parts of the top of the table opaque to X-rays, including members of material opaque to X-rays, relatively movable to vary the transparent field of the table-top, and guiding means for said first-named means.
